UNITED STATES PATENT OFFICE.

CULVER D. YETTER, OF TOPEKA, KANSAS.

BOOK INDEX.

Application filed April 10, 1923. Serial No. 631,125.

The invention relates to an improved method and means for paging a sheet with printed matter of the kind ordinarily found in State statutes, pamphlets, and books. 5 The invention, however, is not being restricted to this particular use.

The invention has more specific reference to number systems for a permanent set of running section numbers combining chapter, 10 article and section numbers and eliminating the dual system of numbering used in all previous compilations and its object is to eliminate the dual system.

Under the system of this invention the 15 numbering used in all compilations previous to the last revision eliminate the dual system of numbering and under this plan section numbers are to be divided by a dash; the dash applying to the particular section. 20 For example, the first section in the sample shown apply to a particular section. On the following page is found the first section of the first article in the chapter numbered, say, 55; on the following page will be found 25 section 55—201, this being the first article of the second article of the same chapter. Thus the number of each section is not only the running section number but also carries within it the number of the section of the 30 article and the number of the section with relation to all the other sections in the same chapter and all other sections in the same volume. This eliminates small chapter, article and section numbers and combines the 35 same with the running section number in a permanent number.

Under the present system of successive number sections the enactment of one new section will entirely derange all numbers of 40 all following sections of later compilations. Under the new system, mounted sections may be inserted in the compilations with the same section number and new articles may be inserted in chapters without disturbing 45 the numbers of other chapters or sections. New sections may be inserted in future compilations following other sections as supplemented or additional legislation by merely using an additional letter or point or 50 number or other symbol. It will be readily observed that this provides for practically unlimited expansion of future compilations without changing the basic numbers. The 55 advantage of such a system giving a permanent reference number, can hardly be over estimated. The numbers of important

chapters being once memorized and chapters frequently consulted are surprisingly few, the necessity for consulting the index is reduced to a minimum.

Memory tests have proved that short numbers are more easily remembered than words, also that numbers divided in this way are far more easily carried in the mind than solid numbers. The chapter and section 60 numbers being both combined and are carried at the upper outside corner of the page, wherefore, it is made possible to turn to any desired place in the volume almost instantly.

This method of numbering is strictly in 70 accord with modern practice as will be noted in Corpus Juris also the latest federal statutes, the revised statutes of Wisconsin and other volumes but the present plan has somewhat simplified the other systems. 75

The statutes of the State are used in connection with the Supreme Court reports almost constantly. In reading a decision of the Supreme Court to which the court has referred to any one of the compilations of 80 previous years it is very difficult to ascertain where such particular section has been printed in the following compilation. Under the old continuous plan of serial numbers a section, say, section 1,000 of one compilation has no connection whatever with section 1,000 of the following compilation. 85

If this system is adopted a section which bears a particular number in the Revised Statutes of say 1923 will bear the same 90 number in any following compilation using this numbering system. New acts will take new numbers but the new numbers will in no way interfere with the numbers of the old sections. Therefore, a decision of the 95 Supreme Court which refers to a section of the Revised Statutes of 1923 by section number will always refer to the same section number so long as that section remains in effect, regardless of how many compilations 100 may intervene. The Supreme Court reports are a permanent record of the construction of the statutes of the State and it is believed that a very great economy of time would result in making the numbering system of the revised statutes as permanent as the Supreme Court reports. In case any section which is permanently numbered in the new compilation is subsequently repealed without constituting enactment the number 110 would be carried in following compilations followed by the word "Repealed" giving

proper reference to the repealing act. This would automatically make every succeeding compilation a complete record of legislation subsequent to the revision.

5 The invention will be best understood from a consideration of the following detailed description taken in connection with the accompanying drawings forming part of this specification with the understanding, however, that the invention is not confined to any strict conformity with the showing in the drawings but may be changed and modified so long as such changes and modifications make no material departure from the salient 10 features of the invention as expressed in the appended claims.

By reference to the accompanying drawing, which drawing is a view of a chosen part of the numbering system and includes 20 a chosen chapter, designated chapter 55, article 1 on partnerships and continuing to chapter 55, article 109 and is to be taken as illustrative of the entire index but it is to be understood the index may be extended to 25 any desired length along the lines suggested in the drawing.

In the drawing, the section of the index illustrated has been chosen as relative to partnerships without limitation to such particular part of the index but will serve as a 30 sufficient illustration to illustrate the index and from which the numbering system may be readily worked out.

It will be observed that the dual system of 35 numbering already referred to is omitted as above stated. Taking a concrete example, the first page of the sample pages is section 55—101. This is the first section in these pages and is the first article in chapter 55. 40 On the following page will be found 55—201 which is to be the second section of the second article of the same chapter. Thus the number of each section is not only the running section number but also carries within 45 it the number of the chapter, the number of the article and the number of the section with relation to all the other sections in the same chapter.

The old form was to number every section 50 in the statute beginning with 1 and consecutively to the end. In the new compilation if there had been one new section, one new law enacted by the legislature this would require the changing of every subsequent section 55 number in the book at great expense. So there has been adopted a modern system which is by chapters and articles. The first number or numbers are the chapters. The second number or numbers are the article 60 and section numbers, every article constituting 100 numbers.

As typical take procedure civil which happens to be chapter 59 in the revision. The first section will be 59—101. This shows at a 65 glance that this is the first section of article

1 of the chapter. 59—201 is article 2 in that chapter. It gives a practitioner and searcher for the section the immediate information as to the chapter and title and returning to the statute he finds at the upper left hand corner 70 the particular chapter and article that he wants so that instead of having to run through 100 or more sections he turns at once to the chapter and article indicated by the number. 75

The advantage of the compilation plan of the scheme outlined above is similar to the modern form of street numbering. Formerly in cities the numbers began at one end of the street and ran consecutively to the other end. As an example, Broadway, New York city is an example of the old style which is retained for sentimental reasons and very confusing. Even old residents of New York do not know where 57 Broadway 85 is without asking a policeman. The modern way is 100 through the block so that one knows 101 always means a corner and anyone familiar with the city knows the exact street number. Similar systems have been 90 adopted by Congress and some of the cities in more recent revisions. It is about the only innovation that the invention proposes.

The most important feature of the system of numbering of this invention is made by 95 the addition of new session laws in a new compilation. For instance, if there is an amendment to some section of chapter 57, article 1 the present number would go in as 57—105 simply added to that article. No 100 other section of the statute would need be disturbed. All other sections of the revision would be exactly as they now are. If there should be no new revision for fifty years every section number would remain as it 105 now is. Amended sections would take the place of the old. New sections would be added to the particular article adding one number to the second series of numbers. Lawyers and others interested in the revised 110 statutes who will learn the chapter and section numbers will be able to find them as rapidly twenty-five years from now, after three or four compilations as they do now. This feature alone makes the new numbering 115 system worth while. It is really the important part of it. It saves much expense in new compilations besides the convenience to be able to refer to well known sections by well known numbers. Year after year the Supreme Court will refer to these same numbers in considering these sections. Instead of having to run through a maze of compiled law where reference is made by sections as is frequent in the decisions of the Supreme 120 Court, there will be one clear section number which will remain or should remain as long as the State has a statute book. 125

In the drawings, there is shown a sheet 1 130 representative of a portion of an index re-

lating to the heading partnerships indicated at 2 while in the upper left-hand corner is a sub-heading 3 referring to chapter 55, article 1 or any other part of the index. Following chapter 5, partnerships, is article 1, limited partnerships designated at 4 and designating various sub-headings thereunder indicated at 5, 6, 7, 8, 9 and 10, all of which is self explanatory.

10 What is claimed is:—

An index for a publication of the class

described, comprising a sheet bearing an index by chapter, article and section number, the chapters being designated by consecutive numbers and each article in said chapter being denoted by a number consisting of three figures, the first digit of which designates the article number and the remaining digits of which designate the section number in said article.

In testimony whereof I affix my signature.

CULVER D. YETTER.
